UNITED STATES PATENT OFFICE

GEOEGE THOMAS BALDWIN, OF THORNTON HEATH, ENGLAND, ASSIGNOR TO REM-
BRANDT INTAGLIO PRINTING COMPANY LIMITED, OF LONDON, ENGLAND, A COR-
PORATION OF GREAT BRITAIN

PRINTING AND OTHER CYLINDER, AND MEANS FOR SECURING SHEETS THERETO

Application filed March 11, 1929, Serial No. 346,192, and in Great Britain January 29, 1929.

This invention relates to printing and other cylinders which are adapted to carry metallic sheets. Such cylinders with the sheets secured thereon are useful for many purposes. The invention, however, relates more particularly to printing cylinders and has for its object to provide an improved cylinder and means for securing a metallic sheet such as a design or impression plate or sheet thereon. The invention is hereinafter described in its application to a printing cylinder, from which the nature of its applications in general will be readily understood.

According to the present invention a printing cylinder is split longitudinally or lengthwise to form at least two parts capable of being assembled with the ends of one or more than one impression or design plate between the parts so as to form a rigid unit as a whole. The printing cylinder may carry one or more than one plate of which either plate or both plates where there are two, may be utilized for printing purposes. Where only one plate is used the peripheral surface of the other cylinder segment may form a surface flush with that of the plate on the other cylinder segment. The two parts of the cylinder hereinafter referred to as the cylinder segments are preferably supported by a rectangular shaft having ends which are reduced to a circular or cylindrical form so as to form journals or bearing portions for the said shaft. The axis of the rectangular portion of the shaft is eccentric to the axis of the circular or cylindrical ends of the shaft, one cylinder segment being keyed to opposite sides of the rectangular portion of the shaft and also supported by studs, set screws, bolts or equivalent screwed into the said cylinder segment and passing through the rectangular portion of the shaft. The bolts or set screws are retained in position against the shaft both by keys and by the bolt heads and/or nuts screwed on to the aforesaid studs. The cylinder segments are provided on adjacent faces with flat or plane surfaces one pair or both pairs of opposite faces having recesses adapted to carry means for securing one or more than one metallic sheet to the cylinder and for placing the sheet or sheets under tension on the peripheral surface of the cylinder formed by the two cylinder segments when assembled. The means for securing one or more than one metallic impression or design plate or sheet in position comprises bars which are rockably disposed in their respective recesses and provided with hooks to which the ends of one or more than one metallic design or impression plate or sheet can be attached. The studs, set screws, bolts or equivalent aforesaid are provided at their outer ends with reduced portions which are adapted to engage in holes in the other cylinder segment so as to facilitate, guide and steady the other cylinder segment when assembling and positioning the latter on the other or keyed cylinder segment.

In order that the invention may be clearly understood and readily carried into effect reference is made to the accompanying drawing which shows diagrammatically and by way of example a construction of printing cylinder in accordance with the present invention.

Figure 1 is a cross section on the line 1—1 Figure 3 of a cylinder in accordance with the present invention showing the cylinder segments in the open position with two impression or design plates engaged by rockable bars.

Figure 2 is a similar view to Figure 1 but showing the cylinder segments in the closed or assembled position.

Figure 3 is an elevation of the cylinder segment mounted on a suitable shaft.

Figure 4 is an end view looking in the direction of the arrow A, Figure 3.

Figure 5 is a cross section on the line 5—5 Figure 3.

Figure 6 drawn to an enlarged scale is a perspective view of one of the rockable bars for use in securing the impression or design sheets or plates in position and also for tensioning the said sheets or plates when assembling the cylinder segments.

Figure 7, drawn to an enlarged scale, is a cross section of a detail hereinafter described.

Figure 8 is a perspective view of a metallic

sheet for use with a cylinder in accordance with the present invention.

Referring to Figures 1 and 2 of the drawing, 1 and 2 are the cylinder segments and 3 is a shaft which at the particular plane of section shown in Figures 1 and 2 is of rectangular section, 4 is the peripheral surface of one cylinder segment and 5 the peripheral surface of the other cylinder segment, 4' and 5' are design or impression plates one on each cylinder segment. The cylinder segments 1 and 2 are provided with flat or plane faces 6, 7, 8 and 9, the faces 6 and 7 being approximately in one and the same plane and the faces 8 and 9 being also approximately in one and the same plane or in parallel planes. The faces 6, 7, 8 and 9 are recessed as at 10, 11, 12 and 13 and adapted to carry bars 14, 15, 16 and 17, the bars 14 and 16 being disposed as to co-operate when assembling the cylinder segments and the bars 15 and 17 being adapted to co-operate also when assembling the cylinder segments. In order to provide for a suitable bearing surface for the bars 14, 15, 16 and 17 the respective recesses are formed by inserted mild steel pieces 18, each of which is shaped as shown more particularly in detail in Figure 7. It will be seen from Figure 7 that the outer surface of each recess is of circular form as shown at 19, each such surface having an inwardly extending peaked portion 20 the use of which counteracts any tendency of a rockable bar to rise out of its rockable position. Such a construction also keeps the rockable bars in their recesses whilst the sheets are being assembled. The bars 14, 15, 16 and 17 are all of the same construction and a description of one bar is considered sufficient, from which description the construction of all the bars may be readily understood. Each bar, say the bar 14, all of which are the same, longitudinally and in cross section comprises an outer surface of suitable curved form as shown at 21 and an approximately flat portion 22 and a suitable curved portion 23. Formed integral with each bar is a number of hooks 24 having under-cut portions 25 which are adapted to engage a wire or rod 26 retained in position one on each end of the metallic design or impression plate 4'. Each end of a design or impression plate, one end of which is shown in Figure 8, is recessed or gapped as shown at 27 and the outwardly extending fingers are bent round on to the surface of the sheet to form loops 28. The loops 28 through which the wires or rods 26 pass may be soldered to the surface of the metallic sheet or otherwise rigidly secured thereto. To accommodate these loops or to allow of the necessary clearance the insert parts 18 are provided with further recesses 29 so that the looped portions have free play when entered and subsequently positioned in the recesses in the inserts 18. The inserts 18 may be secured to the respec-

tive cylinder segments by bolts, studs, screws or other suitable means.

The shaft 3 is provided with reduced circular or cylindrical ends 30, 31, 32, 33 which form journals or bearings for the shaft. The axis of the cylindrical portion of the shaft is shown at 34 and the axis of the rectangular portion of the shaft is shown at 35 in Figure 3. The ends of each cylinder segment are reduced to form a truncated conical portion 36 adapted to receive a retaining ring 37 one of which is held in position against each face 38 formed by the assembled cylinder segments by means of set screws or equivalent 39. A retaining ring such as 37 is disposed at each end of the cylinder segments such rings acting to retain the cylinder segments in the assembled position on the rectangular shaft 3. The cylinder segment 2 as will be seen more particularly from Figure 5 is retained in position against the shaft by studs 40 the upper ends of which are reduced as at 41 so as to engage holes 42 provided in a flat face 43 formed on the cylinder segment 1. 44 are the bolt heads which retain the cylinder segment 2 against the face 45 of the shaft 3. The said cylinder segment 2 is also keyed as at 46, 47 to the sides 48, 49 of the shaft 3 and in order to reduce the weight of the cylinder segments each segment may be recessed as at 50 and 51.

The rings 37 are of concave form on their peripheral surface so as to prevent the ink spreading.

When assembling the cylinder segments in position, the segment 2 is placed on a suitable flat surface and the shaft 3 is then dropped into or placed in position. The shaft is then secured to the segments 2 by the bolts 40, and the shaft and cylinder segment 2 slipped into the usual U-shaped rockable bearings. Before or after turning the usual U-shaped bearings to their vertical position the cylinder segment 1 is placed in position on top of the cylinder segment 2. It should be clearly understood however, that the hook bars 14, 15, 16 and 17, together with the impression or design plates or sheets are in position between the cylinder segments, before superimposing the cylinder segments. When the cylinder segments have been superimposed the cylinder is then rotated against an impression cylinder or other suitable cylinder or roller which forces the rockable bars into the position shown in Figure 2, thus, not only completely assembling the sheets 4' 5' in their proper relative position but also tensioning the said sheets at the same time. The rings 37 are then placed in position and secured by the set screws 39. The cylinder thus assembled then forms a rigid unit with a metallic design or impression plate or plates under tension. To facilitate separation of the cylinder segments and the detachment of one or other of the design

or impression sheets or plates the cylinder 1 may be provided with screw-threaded holes 52, 53, into which, after removal of the rings 37, set screws can be inserted so as to start removal of the cylinder segment 1. After the cylinder segment 1 has acquired a suitable lift or rise the said cylinder segment, as well as the design or impression sheet carried thereby, can be readily and quickly removed, replaced and/or renewed when desired. After removal or sufficient lift or rise of the cylinder segment 1 the design or impression plate around the peripheral surface of the cylinder segment 2 can be removed, replaced and/or renewed when desired.

What I claim is:—

1. A printing or other cylinder wherein the cylinder is split longitudinally or lengthwise to form at least two segments, both segments being carried or mounted on a rectangular shaft having reduced circular or cylindrical ends, and rings embracing both segments and rigidly secured to the ends of the said segments to retain said segments in operative association.
2. A printing or other cylinder wherein the cylinder is formed in two longitudinal cylinder segments, one cylinder segment being secured to and supported by a rectangular shaft and the other segment being loosely supported on the rectangular shaft and on the other cylinder segment.
3. A printing or other cylinder wherein the printing cylinder is split longitudinally or lengthwise to form at least two segments, a rectangular shaft with which both segments cooperate, the adjacent faces of the two cylinder segments being provided with recesses having outer curved surfaces, rockable bars in the said recesses, a metallic design or impression plate having its ends secured to the rockable bars arranged to cooperate with any one segment.
4. A printing cylinder constructed in segments, and a rectangular shaft to support the segments, one cylinder segment being keyed to the sides of the rectangular shaft, the other cylinder segment being unconnected with the said shaft and having holes adapted to receive pins to guide and facilitate superimposition of the one cylinder segment on the rectangular portion of the shaft and also on the other cylinder segment.
5. A printing or other cylinder wherein the cylinder is divided longitudinally into at least two segments adapted to be superimposed on each other, a rectangular shaft to support the segments, and a metallic sheet having its ends held between the segments, the shaft having cylindrical ends, the axis of which is displaced relative to the axis of the rectangular portion of the shaft.
6. A printing or other cylinder constructed in segments, a rectangular shaft on which the segments are supported, one segment being keyed to the sides of the rectangular shaft, the other segment being unconnected with the shaft and formed with holes to receive guiding means to facilitate superimposition of such segment on the rectangular portion of the shaft and on the other segment, one such segment being removable from the shaft without displacement of the other segment.
7. In a longitudinally split printing cylinder, a rectangular shaft adapted to receive and support at least two segments, a design plate superimposable on the cylinder segments and having its ends extending inwardly between two separating faces of the cylinder segments, and means disposed between the said separating faces and adapted to engage the inwardly extending ends of the design plate so as to apply tension to the said design sheet during assembly of the cylinder segments, and means to retain the cylinder segments in assembled position on the said rectangular shaft.
8. In a longitudinally split printing cylinder, a rectangular shaft adapted to receive and to support at least two cylinder segments, design plates superimposable on the cylinder segments and having their ends extending inwardly of and between the cylinder segments, means loosely engageable with the ends of the said design sheets and adapted on assembly of the cylinder segments to apply tension to the design plates, and means to retain the cylinder segments in assembled position.
9. In a longitudinally split printing cylinder, a rectangular shaft, two cylinder segments recessed throughout their length to conform to the rectangular form of the rectangular shaft and superimposable thereon, two design sheets having their ends extending inwardly between the said cylinder segments, means loosely engageable with the ends of the design plates, means to apply tension thereto during assembly of the cylinder segments, and means to retain the cylinder segments with the design plates assembled thereon in assembled position.
10. In a longitudinally split printing cylinder, a rectangular shaft, cylinder segments superimposable thereon, design plates overlying the cylinder segments and having their ends extending inwardly of and therebetween, means disposed between the cylinder segments and engageable with the ends of the said design plates and rockable by assembly of the cylinder segments to tension the design sheets, and means to retain the parts in assembled position.
11. In a longitudinally split printing cylinder, a rectangular shaft, two cylinder segments at least superimposed thereon, reduced circular ends on the said rectangular shaft, design plate tensioning means between the segments, and rings embracing both segments and rigidly secured thereto so as to

retain the cylinder segments in operative association.

12. In a longitudinally split printing cylinder, a rectangular shaft, two cylinder segments at least superimposable thereon, tensioning means between the segments, reduced circular ends on the rectangular shaft having their axes aligned to form an axis common to both circular ends and displaced relatively to the rectangular portion of the said shaft.

13. In a longitudinally split printing cylinder, a rectangular shaft, two cylinder segments supported thereon, design plates superimposed on the cylinder segments and having their ends extending inwardly of and between the said segments, rockable means disposed between the segments to apply tension to the design plates, and means to retain the rectangular shaft, the cylinder segments, and the design plates in assembled position.

14. In a longitudinally split printing cylinder, a rectangular shaft, reduced circular ends thereon having a common axis displaced relatively to the axis of the rectangular shaft, two cylinder segments supported on the said shaft, design plates overlying the peripheral surface of the cylinder segments and having their ends extending inwardly of and between the said segments, means disposed between the segments to apply tension to the design plates when assembling the cylinder segments, and means to retain the parts in assembled position.

15. In a longitudinally split printing cylinder, a rectangular shaft, cylinder segments superimposed thereon, design plates overlying the peripheral surface of the cylinder segments and having gapped ends, wires rigidly secured to the said ends, means loosely engageable with the said wires and adapted to be rocked to apply tension to the design plates when assembling the cylinder segments, and means to retain the parts in assembled position.

16. In a longitudinally split printing cylinder, a rectangular shaft, two cylinder segments mounted thereon, design plates superimposed thereon and overlying the peripheral surface thereon, rockable means disposed between the cylinder segments and loosely engageable with design plates to apply tension thereto, and rings adapted to be rigidly secured to the ends of the cylinder segments so as to retain the parts in the assembled position.

17. In a longitudinally split printing cylinder, a rectangular shaft, two cylinder segments supported thereon, design plates superimposed on the cylinder segments and having their ends extending inwardly of and between the said segments, rockable bars disposed between the segments, hooks on the said bars and loosely engageable with the ends of the design plates and adapted by butting contact to apply tension to the design

plates when assembling the cylinder segments on the rectangular shaft, and means to retain the parts in the assembled position.

18. In a longitudinally split printing cylinder, a rectangular shaft, two cylinder segments supported thereon, design plates superimposed on the cylinder segments, pairs of bars interposed between the opposed ends of the design plates, undercut hooks on the said bars adapted to engage the design plates and rockable with the said bars by abutting contact of the hooks when assembling the cylinder segments to apply tension to the design plates, and means rigidly secured to the ends of the cylinder segments to retain the parts in their standard position.

19. In a longitudinally split printing cylinder, a rectangular shaft, a cylinder segment rigidly secured thereto, a second cylinder segment loosely supported thereon and on the rectangular shaft, a design sheet overlying each cylinder segment and having its ends extending inwardly of and between the said segments, tensioning means between the cylinder segments and adapted by butting contact to rock and tension the design plates, and means to secure the parts together as a rigid whole.

20. A printing cylinder split longitudinally to form at least two segments, a rectangular shaft on which the said segments are mounted, adjacent faces of the two segments being adapted to receive means loosely engageable with the end of a design plate assembled in position between the two cylinder segments.

21. A printing cylinder split longitudinally to form at least two cylinder segments, a rectangular shaft having one cylinder segment keyed to the sides thereof, the other cylinder segment being loosely superimposed on the shaft and adapted to receive pins securing the other cylinder segment to the rectangular shaft, the said pins acting as guides to facilitate superimposition of the one cylinder segment on the rectangular portion of the shaft and also on the other cylinder segment.

22. A printing cylinder split longitudinally to form at least two segments adapted to be superimposed on and carried by a rectangular shaft, one of said segments being removable from the shaft without displacement of the other cylinder segment, and design plate tensioning means operable between the cylinder segments.

23. A printing cylinder split longitudinally to form at least two cylinder segments, a design plate superimposed on and overlapping the ends of the said cylinder segment, the other cylinder segment being formed with a plane surface flush with the surface of the design plate on the associated segment, and a rectangular shaft adapted to engage and support both cylinder segments.

24. A printing cylinder split longitudinally

to form at least two segments, a design plate superimposed on and overlapping the ends of one of said segments, a plain metallic plate superimposed on and overlapping the other segment, a rectangular shaft having the cylinder segments supported thereon, rockable means disposed between the cylinder segments to tension the design plate, and means to retain the parts in assembled position.

10 25. In a longitudinally split printing cylinder, two cylinder segments, each having a rectangular recess in its meeting face, a rectangular shaft adapted to engage in the recesses in the cylinder segments, design plates superimposed on the cylinder segments with their opposite ends disposed therebetween, means disposed between the meeting faces of the cylinder segments engageable by opposite ends of the design plates and adapted to tension the latter during assembly of the cylinder segments, and rings embracing the cylinder segment ends and rigidly secured thereto so as to retain the cylinder segments in assembled position.

25 In testimony whereof I have hereunto signed my name.

GEORGE THOMAS BALDWIN.
